UNITED STATES PATENT OFFICE.

JULES LARDINOIS-PIGEON, OF DAVERDISSE, NEAR WELLIN, BELGIUM.

BROODER.

No. 884,935.

Specification of Letters Patent.

Patented April 14, 1908.

Application filed January 11, 1907. Serial No. 351,855.

To all whom it may concern:

Be it known that I, JULES LARDINOIS-PIGEON, a subject of the Belgian King, residing at Daverdisse, near Wellin, Belgium, have 5 invented new and useful Improvements in Brooders; and I do hereby declare the following to be a full, clear, and exact description of the same.

The object of my present invention is to 10 provide a chicken-breeding device, comprising a special water-boiler from which warm water constantly passes into flat circulating pipes, arranged under a suitable shelter formed of a heat insulating roof below which 15 the chickens are sheltered in a perfect manner.

In the accompanying drawings I have 20 shown a form of construction of my invention, and in these drawings: Figure 1 is a perspective view of my improved chicken-breeding device proper with the outer box removed. Fig. 2 is a longitudinal section of same. Fig. 3 shows a cross-section on line *a—a* of Fig. 2 and Fig. 4 shows 25 a cross-section on line *b—b* of Fig. 2.

The breeding device proper is formed of two main parts: the water-boiler A and the shelter B.

The water-boiler is formed of a casing 1, 30 preferably of rectangular sections, and divided internally by a partition 2 into two chambers 3, 4, the one 3 of which forms the water container and the other 4 the hearth. The latter contains a lamp 5, the combustion 35 gases of which are discharged through a chimney 6. The upper wall of the casing 1 has an opening 7 through which the feed water is introduced into the boiler. At the rear upper end, the latter is connected with a flat 40 pipe 8, arranged horizontally below a common roof 9, each longitudinal edge of which is provided with a depending curtain 10, made of cotton or flannel. The space comprised between the pipe 8 and the roof 9 is 45 filled with suitable heat insulating material

11 viz. saw-dust or the like. The warm water produced in the boiler 3 first passes through the said pipe 8 towards the rear end of the shelter, and then flows back to the boiler through a flat vertical pipe 12 made in 50 the form of a partition and dividing the shelter longitudinally into two chambers, the bottoms of which are formed of a suitable floor 13. The length of the shelter B which is thus maintained at a constant and suitable 55 temperature, may be varied from one to four meters according to the number of chickens to be sheltered.

The shelter B may be raised according to the growth of the chickens, by placing a suitable wooden bar between the floor 13 and the vertical pipe 12.

The device herein described, is preferably housed within a box 14 made of suitable material and the front side of which is provided 65 with two glass doors 15, 15, through which the shelter and boiler are introduced and which serve also ventilating purposes.

Having fully described my invention, what I claim and desire to secure by Letters Patent is:—

In a brooder, the combination of a water-boiler, a flat horizontally arranged pipe communicating with the boiler at one end, a flat vertically arranged pipe communicating at 75 one end with the other end of said horizontal pipe and at its other end with the boiler, said vertical pipe being arranged under the horizontal pipe, and a roof, extending over said pipes and having a depending curtain on 80 each side of said pipes, substantially as described.

In testimony whereof I have signed my name to this specification in the presence of two subscribing witnesses.

JULES LARDINOIS-PIGEON.

Witnesses:

CHARLES HOWARD,
GREGORY PHELAN.
